UNITED STATES PATENT OFFICE.

GEORGE ADSIT, OF PATERSON, NEW JERSEY, ASSIGNOR TO BENJAMIN EASTWOOD COMPANY, OF PATERSON, NEW JERSEY, A CORPORATION OF NEW JERSEY.

QUILLING-MACHINE.

1,186,641.

Specification of Letters Patent. Patented June 13, 1916.

Application filed April 21, 1914. Serial No. 833,370.

To all whom it may concern:

Be it known that I, GEORGE ADSIT, a citizen of the United States, residing at Paterson, in the county of Passaic and State of 5 New Jersey, have invented certain new and useful Improvements in Quilling-Machines, of which the following is a specification.

In Letters Patent No. 1,063,235 I have set forth a cop winding mechanism designed 10 especially for the winding of cops and the like having conical ends in which the thread guiding portion of a thread-guide and a carrier for the thread-guide are pivoted on axes crossing the axis of winding, whereby said thread-guide portion (shown in the form of a split blade), as the thread-guide was moved back and forth with the oscillating carrier, would remain 15 in a definite relation (parallel) to the axis of winding; and in which, further, the thread-guide was itself pivoted in the carrier on an axis crossing the latter's axis of movement, whereby as the building of the cop progressed and the gradually augmented 20 package moved the thread-guide on its pivot in the carrier and hence toward the latter's axis of movement the stroke of the thread-guide portion of said thread-guide would be gradually reduced, thus 25 forming conical ends on the package.

The object of the present invention is to provide a winding mechanism of a type similar to that above referred to yet possessing certain structural and functional advantages thereover. To this end, instead of pivoting the carrier in some fixed part of the frame of the machine, in the present case it is arranged to rock on an axis crossing the axis of winding in a suitable supporting 30 member movable back and forth, the rocking thereof (required for gradually reducing the stroke of the thread-guide in the way to be explained) being accomplished by any suitable means, as by its being pivotally connected with a part of the support in which said member moves.

In the accompanying drawings, Figure 1 is a vertical sectional view of so much of a quilling machine constructed in accordance with this invention as is necessary for the purposes of this description; Fig. 2 is a plan of what appears in Fig. 1; Fig. 3 is a left-side view of the thread-controlling

mechanism; Fig. 4 is a vertical sectional view taken through the axis of rocking 55 movement of the carrier; Figs. 5, 6, 7 and 8 are detail views of the carrier, slide and thread-guide; and, Fig. 9 shows the carrier and the thread-guiding blade *s* in their relative positions at one end of the stroke 60 thereof and the manner in which the detents *z* act to prevent tilting of said blade at this time.

The frame *a*; spindle *b* journaled therein and the means for rotating the same; the support *c* for the spring-pressed plunger *d* which coacts with the spindle to support the pin *A* driven by said spindle; and the bracket *e* are or may be all substantially the same as in my patent aforesaid, excepting 70 that in the present instance said bracket includes a pair of guide-rods *f* arranged parallel with the winding axis. On these guide-rods as a support is arranged the slide or cross-head *g* affording a member to 75 support and having an enlarged cylindrical bearing portion *h* in which is arranged to rock the cylindrical portion *i* of the carrier *i* confined in said bearing portion by an upwardly projecting arm *j* and a disk *k* 80 which bear against opposite ends of said bearing portion, the arm being preferably integral with said bearing portion and the disk secured thereto by screws *l*. The arm has a sliding connection with some fixed 85 part, as the screw *m* tapped into one of several vertically arranged holes *n* in bracket *e* preferably perpendicularly above the mid-position of the slide in its travel on the guide-rods, the screw being provided with 90 a wearing piece *o* received in a slot *p* extending longitudinally of said arm.

The thread-guide means includes an arm *q* which is fulcrumed in the cylindrical portion of the carrier on an axis—a pin *r*—95 which is at right angles to that of the carrier and, as here shown, horizontal when the slide and carrier are in their mid-position, the arm *j* projecting vertically. Said means further includes a thread-guide 100 proper comprising a split blade *s*, a thread-guiding eyelet *t* suitably fixed over the blade and an axial support *u* for the blade journaled in the arm *q* on an axis at right angles to pin *r* and having a fixed head *v* at one 105 end, to which the blade may be soldered,

and a removable collar *w* at the other, said head and collar confining said support *u* against endwise movement. To accommodate the arm *g*, which extends through the cylindrical portion of the carrier, the disk *k* is provided with a slot *k'*.

q' is a spring connecting screws *q''* of the arm *g* and carrier *i* and normally holding the blade end of the thread-guide down.

10 *x* is a bent wire suitably secured to the slide *g* and affording a rest which maintains the blade of the thread-guide elevated when there is no pirn in place.

15 The forward end of arm *g* is provided with a head *y* extended laterally in both directions and having downwardly converging faces from which project the adjustable detents *z* in the form of screws, the same being adapted to contact with the top surface of the blade in the oscillation thereof for a purpose to be explained. Between the heads of the screws and the head *y* springs *z'* are coiled about the screws, serving to lock the latter against turning when adjusted.

25 For supporting the thread-guide elevated when not in use I provide the spring loop 2 secured to a suitable part of the carrier (for instance, disk *k*) and the hook 3, the latter being formed on the arm *g* and adapted, when arm *g* is sufficiently raised, to snap over the loop and hold the arm elevated.

30 The slide is reciprocated through the medium of the hook 4 from the oscillating arm 5 and, the spindle and pirn being rotated, during the progress of the winding the thread is formed around the pirn in a succession of layers of coils. As the winding proceeds the package gradually elevates the guide, whose blade 3 rests thereon, remaining substantially horizontal at all times and oscillating in the arm *g* on an axis at right angles to the axis of winding. This produces a gradual shortening of the 35 stroke of the thread guiding portion of the thread-guide, and consequently of the layers of windings, because the thread guiding portion of the thread-guide, with the axis of the latter tilted, stands less advanced at the end of the stroke when the thread-guide has been elevated than when it is depressed. In other words, with reference to any point on the slide to which the thread guiding portion of the thread-guide would be opposite at the mid-position of the slide, the more the thread-guide is elevated the more as it moves from mid-position to right or left and becomes at the same time tilted will its thread guiding portion fall behind said point. The gradual reducing of the stroke 40 of the thread guiding portion of the thread-guide with consequent gradual shortening of the layers of the coils in the package, of course results in the latter being formed with conical ends.

50 By altering the position of the screw *m* in the holes *n* the degree of taper of the ends of the package may be varied, as will be obvious, because thereby the angle of tilting of the axis of the thread-guide at the ends 70 of the stroke is changed.

The detents *z* serve to maintain the blade *s* against tilting into parallelism with the surface of the cone of the package when at each end of the package. They should be 75 so adjusted that each will just contact with the blade when the latter is at the end of the stroke (Fig. 9), such adjustment being of course necessary whenever the length of the stroke is changed to change the length 80 of the cops being wound.

85 The peculiar construction and arrangement of the parts including the rods *f* and the cylindrical bearing portions *h*, *i'*, with the thread-guide partly housed in the latter, obviously promote compactness, simplicity of construction, the reduction of lost motion and a material postponement of wear with lost-motion as a consequence,—qualities which are important in a mechanism of 90 this character where space is limited and high speed without sacrifice of regularity and compactness in the windings is desirable.

Having thus fully described my invention, 95 what I claim as new and desire to secure by Letters Patent is:—

1. In combination, a support, a rotary spindle, a supporting member reciprocated in the support lengthwise of the spindle 100 axis, a rocking carrier, the carrier and said member having coaxial cylindrical portions one forming a journal for the other and arranged with their axis crossing the spindle axis and said carrier having a rocking-movement-effecting engagement with the support, and a package engaging thread-guide projecting through said cylindrical portions and pivotally supported by the carrier on an axis crossing the axis of said 110 cylindrical portions.

105 2. In combination, a support including opposite parallel guiding surfaces, a rotary spindle parallel with said surfaces, a supporting member sliding longitudinally of 115 between and bearing against said surfaces, a rocking carrier movable in said member on an axis crossing said surfaces and extending between them and having a rocking-movement-effecting engagement with a part of the support, and a package engaging thread-guide pivoted in said carrier on an axis crossing the first-named axis.

120 3. In combination, a rotary spindle, and means, movable back and forth substantially lengthwise of the spindle axis, for laying the thread around the spindle axis in a series of gradually shortening layers of coils, whereby to produce a cone at one end of the package, said means including a 130

rocking supporting structure and a thread
guiding device pivoted in said structure on
an axis crossing the spindle axis and said
structure having an adjustable detent to
5 contact with said device at one side of its
pivot when said structure is at one end
of its stroke.

In testimony whereof I affix my signature
in presence of two witnesses.

GEORGE ADSIT.
